SYSTEM AND METHOD OF REGULATION

Allen M. Rossman, Wilmette, Ill., assignor to
Rossman Engineering Company, a corporation
of Illinois

Application January 29, 1930, Serial No. 424,380
Renewed September 19, 1934

60 Claims. (Cl. 236—14)

My invention relates to a system and method of regulation.

While the particular embodiment which I shall herein describe comprises an automatic system of combustion control for boilers or the like, the invention is not to be restricted to such use.

The present invention is an improvement upon the system and method disclosed in my co-pending application, Serial No. 411,336, filed December 10, 1929.

In controlling combustion the prime desideratum is to maintain a value of combustion which is proportioned to the steam or other load to be carried. The next desideratum is to do this 15 efficiently.

As atmospheric air is substantially constant in composition and as the efficiency of the furnace and boiler is substantially constant, the amount of air required to develop the necessary heat for

20 carrying the load is substantially directly proportional to the load. The fuel—such as powdered coal in this instance—may then be fed at a rate which will secure substantially complete and efficient union with the oxygen of the air.

25 The efficiency of combustion may be checked either automatically or manually, by a CO_2 meter or, after calibration of the installation, by a steam flow—air flow meter. A steam flow—air

30 flow meter is more convenient and prompt in operation than a CO_2 meter and I show the same as a suitable element for checking the efficiency of combustion and making adjustment of the controls accordingly, but it is to be understood that 35 any suitable means which will determine the efficiency of combustion may be employed instead.

The air flow in the present instance is maintained by one or more forced draft fans and one or more induced draft fans. The relation be-

40 tween their actions is reflected in furnace pressure. Hence, by the use of a furnace pressure gauge the ratio of induced draft to forced draft may be ascertained and by suitable responsive mechanisms maintained as desired.

45 The furnace and boiler may be calibrated to determine the various absolute values of air flow and coal feed to steam flow and a general or mean relation established, which will be substantially correct for various loads within the 50 range of the unit. The regulating system is then required to provide regulation only for deviations from the said mean relation.

In the preferred embodiment of the present 55 invention as well as in the system of the above recited application, I employ variable speed drives

for controlling directly the rates of fuel feed and air feed. The air feed is divided between forced draft fans and induced draft fans, each fan driven by a variable speed drive. These variable speed drives are under rheostat control and hence 5 regulation and control are greatly simplified.

Assuming that combustion is proceeding at a fixed rate and the steam demand is increased, such increased demand will be reflected in a reduction of boiler pressure. I employ the steam 10 pressure gauge as a master gauge to control in common the speed of the forced draft fans, the induced draft fans and the coal feeders.

The controller of my invention proportions the 15 rate of correction to the amount of deviation in a novel and efficient manner which, at the same time, takes care of the conflicting requirements of the furnace pressure gauge and the efficiency meter gauge.

While the steam pressure gauge is the master 20 controller, the furnace pressure gauge and the efficiency gauge preempt control of the proper elements to maintain furnace pressure and efficiency, cutting out at the same time the master control. This is desirable because the master 25 controller effects changes according to the aforesaid mean or general relation and the special controls are required to cut in when deviations from the mean are required for the sake of proper 30 efficiency or proper coordination of the induced and forced draft fans. Hence, the special controls cut in and assume control and are caused to act more speedily than the action of the master controller.

My invention performs another desirable function 35 in a novel manner. When the number of boilers operate to supply a common load the division of work performed or load carried must be properly controlled.

In the preferred embodiment the speed of the 40 coal feed motor, hence, the rate of combustion, for each furnace, is varied in proportion to the variations of potential impressed upon the armatures of the motors, which are D. C., separately excited motors.

Now, by suitable voltage regulation of the impressed voltage of any particular set of coal feed motors a suitable rate of combustion is established. Such voltage may be established by comparison with the voltage impressed upon the coal 50 feed motors of one boiler which is selected as the master boiler.

If the boilers are to be equally loaded a substantially 1:1 ratio of such voltages is maintained. Where a boiler is to be operated at reduced load 55

the voltage is suitably reduced upon the coal feed motors thereof to reduce their speed.

Automatic regulation at the reduced load of one boiler may then be maintained by response 5 of the rheostat adjusting motor in proportion to the ratio of load to be carried by such one boiler to the load carried by the master boiler.

In my prior system of regulation periodic control over the speed of the induced draft, forced 10 draft and coal feed, or any of them, was given to the steam pressure gauge, the fire-box pressure gauge and the efficiency meter, in succession, by a series of rotary distribution switches. These switches gave each controlling gauge, or meter, a 15 definite period or time of control.

According to the present invention the steam pressure gauge is the master controller and it is periodically given control of the coal feed, induced draft and forced draft to raise or lower the same. 20 The periods of control are proportioned to the degree of deviation from normal.

My invention provides means for automatically maintaining a predetermined division of load between boilers. In proportioning the load of the 25 various boilers one of the boilers may be considered as the master boiler and the others regulated with respect to it. Since the generation of steam in a particular boiler depends, primarily, upon the rate at which fuel is burned thereunder, the proper proportioning of the rate of fuel burning under 30 the respective boilers will result in the proper proportioning of load between or among them.

In the preferred form of the invention I regulate the speed of the coal feed motors by varying 35 the potential impressed upon the motor armatures; by means of a suitable balanced relay the voltages upon the coal feed motors of the respective boilers may be compared and a certain voltage relation between the coal feed circuits of 40 the respective boilers maintained.

The air supply mechanism which includes forced draft and induced draft fans is then automatically regulated to correspond to the rate of coal feed to maintain the proper combustion efficiency and the induced draft fan and forced draft fan are adjusted with respect to each other to 45 maintain the proper furnace pressure.

It will be observed in the preferred embodiment 50 of the invention that the master controller involves the master pressure gauge which is preferably a steam pressure gauge connected to the delivery main of the boilers. Any suitable device responsive to the load of the boilers may be considered the equivalent of the steam pressure 55 gauge.

The field of this invention is not limited to furnaces for heating boilers. Any furnace heated by combustion may be controlled by this system. In some cases; such as, in metal heating furnaces, 60 the master control device may be responsive to such elements as temperature in the furnace, temperature of the heated product, etc. In some of these applications it may be desirable to install a master controller on each furnace but the principles of operation will be the same. As one of the largest applications of automatic combustion control, however, is in connection with boiler furnaces, a description of this type of control system is made the basis of this disclosure.

70 The master controller also includes an intermittent contact device which serves to regulate the air and fuel supply of any number of boilers which are under automatic control. This intermittent contact device has "off" periods and "on" 75 periods, alternately, the "on" periods effecting a

regulation of the fuel supply and air supply. Due to the fact that the response of the fuel supply mechanism is not immediately felt in the firebox it is desirable to make a regulating adjustment and then wait for the same to take effect before carrying the regulating adjustment further. It is for this reason that an intermittent regulating adjustment is performed.

I have provided, in conjunction with the intermittent contact device, means for varying the 10 length of the "on" periods in accordance with the deviation from normal or balanced position of the master gauge or other load responsive device, so that for greater deviations from normal greater 15 regulating adjustments are effected. Since the response of the air supply means is substantially instantaneous, or relatively prompt as compared to the response of the fuel supply means, the adjustment under the control of the efficiency 20 meter for increasing or decreasing the rate of air supply is made to follow automatically the rate of fuel supply, under the control of two separate 25 controls, namely, first the master controller, which regulates the fuel and air supply simultaneously, according to a predetermined ratio, and next, under the control of the efficiency meter or the like, which adjusts independently of the master controller and to the exclusion of the same, the air supply means.

As between forced and induced draft a relative 30 adjustment is made in addition to the main adjustment of the two fans made by the master controller by means responsive to the furnace pressure which, acting upon the induced draft fan, adjusts its speed relative to the speed of 35 the forced draft fan to maintain the proper pressure in the fire box at all times. This latter adjustment is independent of the master controller and acts to the exclusion of the latter.

Now, in order to acquaint those skilled in the 40 art with the manner of constructing and operating a device according to my invention, I shall describe, in connection with the accompanying drawings, a system embodying the present invention.

Figure 1 is a diagram of a boiler plant to which my system of regulation may be applied.

Figure 2, consisting of three sheets, is a diagram of the regulating system, Figure 2, part 1, indicating the fuel feed and air supply means 50 with their regulating mechanism for one boiler and showing also the balancing relay for proportioning the load between boilers.

Figure 2, part 2, indicates mechanism of the same type shown in Figure 2, part 1, for boiler number 2 and indicates the same, partly, for boiler number 3, and

Figure 2, part 3, shows the master controller.

To assemble the complete diagram of Figure 2, part 2 is joined to the right of part 1 and part 3 is joined to the bottom of parts 1 and 2.

Referring first to Figure 1, I have shown herein diagrammatically the main operating and control parts for a power generating boiler 1, which may be of any suitable type. This boiler 1 is provided with a steam pressure gauge 2 of a type suitable to operate the electrical controls hereafter to be described. The fire box 3 is shown in this case as fired with powdered coal through two sets of nozzles, 4 and 5 respectively, having individual means for supplying powdered coal thereto. While the invention is herein shown as embodied in a steam generating plant employing powdered fuel it is to be understood that

this is merely by way of illustration and not of limitation.

The furnace 3 is fed with coal and air by duplicate apparatus for each, mainly for the sake of reliability. The nozzles 4 and 5 receive their mixture of powdered coal and air through a passageway 6 from the coal pulverizer 7, this mixture being moved by the exhauster 8 driven by a suitable driving motor 9.

10 Fuel from a suitable source of supply is delivered by a pair of coal feeders 10—10 from the hoppers 13. The feeders 10 are driven by feeder motors 12, the speed of these motors being regulable in order to control the rate at which 15 fuel is supplied to the boiler. This motor 12 may be a variable speed motor, for example, a D. C. motor or it may be a variable speed A. C. drive, hereafter described. The pulverizer 7 has a grinding mill 14 driven by a variable speed electrical drive 15. The exhauster motor 9 may be driven at substantially constant speed although this may be a variable speed motor or drive if desired.

Primary air for carrying the pulverized fuel 25 is supplied to the pulverizer 7 through the duct 16, this duct leading from the forced draft supply duct 17 leading from the air heater 18. A controlling damper 19, operated by a pilot motor 20 controls the air supply through the duct 30 16. In other words, the damper 19 regulates the primary air supply.

The nozzles 4 are fed with fuel and primary air by apparatus shown at the left of Figure 1, which is a duplicate of that shown at the right 35 of Figure 1 and having primed reference numerals applied thereto to designate like parts.

The main air supply to the furnace 3 is furnished by a pair of forced draft fans 22 and 22', driven by variable speed drive mechanisms 40 23, 23'. These fans 22 and 22' deliver air through the conduits 24, 24' to the air heater 18, 18', which is heated by the exhaust gases after they pass through the economizer 25.

After the air passes out of the air heater 18 45 into the conduits 17, 17', the major volume of the same is delivered to the furnace 3 through the secondary air supply ducts 26, 26'. The main volume of air is supplied through the ducts 26, 26', the air supplied through the ducts 16, 16' being insufficient to support complete combustion of the fuel and serving rather as a carrier of the fuel to bring it into the furnace 3 where it mixes with the main air supply which is required to support combustion.

50 The products of combustion pass up through the tubes of the boiler 1, then through the economizer 25, then through the air heater 18 and thence to the conduit 27 leading to the stack 28.

The conduit 27 is divided into two channels, 60 29, 29', leading to the induced draft fans 30, 30', which are driven at any desired speed within limit by the variable speed driving devices 32, 32' which may be of a character similar to the devices 23, 23' for driving the forced draft fans.

65 The pressure of air in the furnace is preferably maintained at a pressure slightly below atmospheric, generally in the neighborhood of 1 of an inch of water. The pressure prevailing in the furnace 3 is indicated upon the furnace pressure gauge 33. When the ratio of induced to forced draft is proper the above stated pressure, slightly less than atmospheric, is maintained within the furnace 3.

70 Obviously, in order to vary the rate of steam delivery by the boiler 1, the amount of heat

developed in the furnace must be likewise varied, assuming a constant condition of efficiency and the like in the boiler and the furnace. Such variation in developed heat means variation of the chemical union of fuel and oxygen of the air. In order to maintain efficient combustion it is necessary that the ratio of fuel to air be maintained at a proper value. Variation of the heat developed, therefore, must be accomplished by simultaneous variation of air supply and fuel supply in order to maintain the efficiency of combustion which is desired. This problem of varying simultaneously the air and fuel is, in the present instance, complicated by the necessity for maintaining the proper ratio of forced to induced draft, or vice versa.

75 The efficiency of combustion is determined by a carbon dioxide meter, generally termed a CO₂ meter; this is indicated at 34 as connected to the conduit 27, through which the products of combustion flow to the stack.

To obtain the best possible combustion efficiency from the boiler it is necessary to mix with the fuel as nearly as possible the correct amount of air to provide two parts of oxygen 25 for each part of carbon in the fuel. If too much air is furnished too much heat is wasted up the stack. If too little air is furnished, insufficient oxygen is supplied and not all the fuel is burned. Air in excess of the amount necessary must be 30 supplied to insure that, so far as possible, each part of carbon comes in contact with the required two parts of oxygen. This is checked by measuring the percentage of CO₂ in the flue gases, this percentage being in the neighborhood of 12% to 35 14% under the best practicable conditions.

Instead of employing the CO₂ meter 34 as means responsive to efficiency of combustion, I may employ a meter 34' which is responsive to the ratio between steam flow and air flow. Such 40 steam flow to air flow meters or responsive devices are known and the construction of the same forms no part of the present invention. Suffice it to say that the flow of air through the furnace may be determined by measuring the drop in pressure of the gases passing through a portion of the furnace or connections and the flow of steam delivered may be measured by means of a Pitot tube or the like, and the two measurements compared in the meter 34' which then responds to 50 the ratio of steam flow to air flow which, for a given fuel, should remain substantially constant, since a predetermined amount of air is required to develop a predetermined amount of steam at constant pressure.

55 With the boiler in continuous operation and connected to the steam main 11, for delivery of steam to a turbine or the like, the load may be assumed to be properly carried, so long as the steam pressure gauge 2 indicates that an adequate pressure is maintained. That is to say, so long as the steam pressure gauge indicates that a constant pressure is maintained, the rate of combustion is proper for the load carried by the boiler.

65 Any deviation of the ratio of combustion to load will be evidenced by rise or fall of steam pressure, which will at once affect the gauge 2. Therefore, with a given speed of the induced draft fans and the forced draft fans for passing a predetermined amount of air through the fire box per unit of time and with a proper setting of the coal feed 10 and damper 19 to supply the necessary fuel for union with a predetermined volume of air and the steam pressure gauge indicating the de- 70 75

sired pressure, the boiler may be assumed to be in proper operation, carrying the load.

While the deviation from normal pressure by the master steam pressure gauge is a satisfactory load responsive device, a steam flow meter which is responsive to steam flow may be employed instead, or any other element which is responsive substantially to B. t. u. delivered by the boiler. The master pressure gauge is a simple load responsive device which fulfills the requirements of the present regulating system.

If the boiler pressure or the measurement of steam flow should drop, indicating that the rate of heat development is not as great as required, fuel and air feed should be simultaneously increased in proportion to substantially a predetermined ratio of air and fuel. This is then to be carried out by the automatic mechanism diagrammatically shown in Fig. 2.

If the resultant ratio of air to fuel is not exactly right to secure the desired percentage of carbon dioxide in the fuel gases as measured by the meter 34, a correction of the ratio of air to fuel feed must be made. Also, in increasing the rate of combustion, the induced draft and forced draft must be simultaneously increased in such a manner as to maintain the furnace pressure at a proper value as determined by the furnace pressure gauge 33.

Now it can be seen that the automatic control system is called upon to vary at least three things, namely, forced draft, induced draft and coal feed, while maintaining a predetermined ratio between total air flow and fuel supply and between forced and induced draft, total air flow in this case being controlled by the two factors, namely, the forced draft fan 22 and the induced draft fan 30.

The system of control shown in Figure 2 is of relatively greater simplicity as compared with devices of the prior art for accomplishing the same object.

Prior systems of automatic combustion control are complicate because prior systems of draft control are complicate. Consider, for example, a system which employs two-speed squirrel-cage motors for driving the fans, a change in load which calls for a change in motor speeds, also calls for the operation of damper controls both before and after the switching operation and, when dropping from the higher to the lower speed, the proper timing of the switching to prevent undue mechanical stresses from being thrown upon the equipment. All of these operations must be controlled by the automatic combustion control system.

The simple variable speed drive which I have recently developed and which is the subject matter of my copending application, Serial No. 275,641, filed May 7, 1928, whereby the speed of the fans may be varied smoothly and continuously throughout their working range, permits the correspondingly simple scheme of automatic combustion control which is herein shown.

This drive will now be described briefly in connection with the operation of the induced draft fan 30, shown at the top center of Figure 2. This drive comprises a squirrel cage motor 37 having the outer part, which is usually the stator, indicated at 38, mounted for rotation and having also the squirrel-cage rotor 39, the shaft of which squirrel-cage rotor 39 is connected to the drive shaft of the fan. The outer rotating member 38 is provided with windings which are supplied

with alternating current through suitable slip rings.

A direct current machine 40 has a stationary field 42 and a rotatable armature 43, the shaft of which is connected to the outer rotatable member 38 of the squirrel-cage motor 37.

A D. C. generator 44 has a stationary field 45 and an armature 46, the armature 46 being connected in series with the armature 43 of the machine 40.

The armature 46 of the generator 44 is driven by an A. C. motor 47 which may be of any preferred type as, for example, either a squirrel-cage induction motor or a synchronous motor.

The main squirrel-cage motor 37 and the motor 47 of the motor generator set 48 are fed in parallel from the A. C. means 49.

While I have shown three phase current supply, and this is preferable, it is to be understood that I am not to be limited to three phase current, as single phase or other type of alternating current supply may be employed.

The field of the D. C. motor 40 is separately excited from the D. C. constant potential supply mains 50. An adjusting rheostat 52 is inserted in the separately excited field circuit for the motor 40 for the purposes of adjustment. This rheostat is suitably adjusted for operation within a certain range and then is not disturbed during variations of speed of the drive, except as the range is changed or for operation of the drive at speeds below that for which the rheostat 53 provides control.

The separately excited field 45 of the generator 44 is supplied with a potential which is varied to control the speed of the drive. A potentiometer type of rheostat 53 is connected across the constant potential mains 50 and the terminals of the field winding 45 are connected to the brushes 54, 55, these brushes being adjusted as shown in the present instance by the pilot motor 56 and a suitable worm drive 57.

The squirrel-cage motor 37 provides the base speed and the direct current motor 40, which is of much smaller rating, furnishes the increase or decrease in speed from the base speed.

The part 38, which is normally the stator of the induction motor is mounted on bearings so that it may be rotated about the same axis as the rotor 39.

The stator may be driven in either direction by means of the small D. C. motor 49, which draws power through the motor generator set 48. The speed of the D. C. motor 40 and its direction of drive are varied by varying the voltage of the generator 44 from maximum positive to maximum negative.

The speed of the fan 30 is increased above the base speed by causing the direct current motor 40 to drive the stator of the A. C. motor 37 in the same direction as the rotor. The speed of the fan then is the sum of the rotor and stator speeds.

The speed of the fan 30 is decreased below the base speed by causing the stator 38 to rotate in the opposite direction to that of the rotor 39. It then drives the D. C. motor 40 as a generator, which forces power back through the series connection between the armatures 43 and 46 and through the A. C. motor 47 back on to the A. C. mains 49. The fan speed then is the difference between the rotor and stator speeds. When the fan speed has reached the lower limit of speed by armature voltage control of the D. C. motor 40, the speed range may be extended still lower by

field control at the rheostat 52 of the D. C. motor 40, if desired.

The H. P. ratings of the two motors 37 and 40 on the induced draft fan 30 are, in the ratio of 5 A. C. motors, seventy-nine per cent (79%) and D. C. motors, twenty-one per cent (21%) in one example of my invention.

The drive for the forced draft fan 22 may be identical with that shown at 32 for the induced draft fan 30. In this particular instance the H. P. rating to the two motors on the forced draft fan is, in the ratio of A. C. motors, 85.5 per cent and D. C. motors, 14.5 per cent. I have shown, however, for driving the fan 22, a variable speed 15 A. C. motor 23 of the wound rotor type, having the collector rings 57 and leads extending to a three phase rheostat 58, having three contactors 59 movable in unison through the gearing 60 by a rheostat motor 62.

20 The coal feed motors 12—12 have separately excited fields 63—63 connected to the constant potential buses 50—50 and the armature circuits are connected to the variable potential coal feed control bus 64. This bus 64 is supplied with variable potential by the motor generator set 65 comprising a squirrel-cage or other alternating current motor 66 operated from the A. C. supply mains 49 and a separately excited direct current motor 67, having its field 68 variably excited 25 through the control of the motor adjusted rheostat 69 and having its armature 70 connected to the bus 64 for the delivery of current at variable potential thereto. The variable speed coal feed drive is of the so-called Ward-Leonard type. The field rheostat 69 for controlling the potential impressed upon the coal feed motors 12 is operated through suitable gearing 72 by a rheostat actuating motor 73. The motors 62, 56 and 73 are similar in having their fields 74 separately excited 30 from the constant potential bus 50 and having their armatures supplied with current from the branch 75 of the bus 50.

35 As will be pointed out later, the master controller, under the direction of the master pressure gauge or other load responsive device, closes the armature circuits for the armatures 76 of said rheostat operating motors, in unison, to drive them forward or backward, as the case may be, in unison, and the armature circuits of these rheostat operating motors are preferably so adjusted 40 with respect to each other that they move at rates which will maintain at all times substantially a predetermined mean ratio of air to fuel and of forced draft to induced draft. The relative 45 rates of adjustment are regulated by individual rheostats 77, 78 and 79 for the motors 73, 56 and 62.

The bus 50 and the branch bus 75 are supplied with direct current through a motor generator 60 set 80, comprising the A. C. motor 82 and a shunt wound exciter generator 83. A disconnecting switch 84 and fuse 85 are indicated in the branch 75 and a rheostat 87 for providing a common adjustment for the motors 73, 56 and 62 is included 65 in the branch 75. The field circuit of the exciter generator 83 has a field rheostat 86 to adjust the voltage impressed upon both branches 50 and 75.

The master controller 88, which includes the master steam pressure gauge 2 and the timing controller 89, increases the speed of the coal feeders, the forced draft fans and the induced draft fans when the rate of steam demand is in excess of the rate of firing. When the steam pressure gauge 2 is employed a drop in steam pressure indicates that increase in firing is required and like-

wise an increase in steam pressure indicates that a reduction in firing is required. The timing controller has a rheostat 90 subject to steam pressure acting upon the gauge 92, or through any other suitable load responsive device, for varying the "on" periods of control of the timing controller 89 with respect to the "off" periods of control. In the present construction the device 92 is a steam pressure responsive element connected to the movable contactor 93 of the rheostat 90 for increasing the resistance in the armature circuit of the driving motor 94 in proportion to the deviation from normal of the steam pressure. Obviously, if any other form of load responsive device were employed instead of the steam pressure gauge 2, the device 92 would be responsive also to deviations of load from the predetermined value.

The driving motor 94 has a separately excited field 95 and has the armature circuit connected in series with the rotary contactor brushes 96 bearing upon the rotating disc 97 having the conducting segment 98 for bridging the brushes 96. The off-normal rheostat 90 is connected in shunt of the brushes 96 and in series with the armature 9 of the motor 94, the field 95 of the motor 94 being separately excited from the constant potential battery bus 100.

The motor 94 rotates continuously, driving the controller shaft 102 through suitable gearings 103. When the conducting segment 98 bridges the brushes 96, these brushes being adjustable to vary the angular space, or part of each rotation during which the brushes 96 are bridged, the motor 94 rotates at maximum speed. As soon as the conducting segment 98 opens circuit between the brushes 96, the off-normal rheostat 90 controls the speed of the motor. If the contactor 93 includes more resistance, the motor 94 rotates at a slower speed during that part of the angular motion when the brushes 96 are disconnected. Now it can be seen that the shaft 102 will have a constant speed during a predetermined part of each rotation and a controllable or variable speed during the remainder of the angular part of the rotation, the variations in speed being made to correspond to the deviations of the position of the load responsive device from normal.

The shaft 102 bears another rotating disc 104 bearing a conducting segment 105 cooperating with a pair of brushes 106, controlling the circuit 107 of the master steam pressure gauge 2, which is a load responsive device.

The battery circuit from the battery bus 100 extends through the brushes 106, wire 108 to 55 the contacting needle 109 of the gauge 2. A pair of stationary contacts 110 and 112 are adapted to be engaged by the needle 109 when it is off of its mean or normal position, selectively. The contact 110 is connected through the relay winding 114 to the return wire 113. The contact 112 is connected through the relay winding 115 back to the return wire 113. Energization of the winding 114 closes a circuit through the relay contactor switch 116 to apply a potential (in this case positive battery) to the "increase" wire 118. The energization of winding 115 closes a circuit through the relay contactor switch 117 to place a potential (in this case positive battery) upon the "decrease" wire 120.

A hand-control switch 122, having a movable contact 123 for engaging the stationary contacts 124 and 125, selectively, is provided for energizing the control wires by hand. A transfer switch 126 selectively puts the increase and decrease 75

control wires 127 and 128 in circuit with either the automatic control 2 or the manual control 122. The increase and decrease control wires 127 and 128 are connected to increase and decrease control wires 129 and 130 which are extended to the controlled mechanism of each of the boilers in the system. The conductors 129 and 130 are thus increase and decrease control bus wires extending to each boiler control station. These master control wires governing increase and decrease, 129 and 130, are connected through load division relays 132, 133 and 134 to each of the three boiler controls, so that an increase or decrease of firing, as found to be necessary by the master pressure gauge 2, can be simultaneously effected upon the combustion control mechanism of each of the boilers in the system. These load division relays are under the control of corresponding voltage differential relays 135, 136 and 137.

The master control wires extend in each case through the corresponding load division relay and to a selector switch 138, 139 and 140. The selector switch 138 puts the individual control wires 149 and 150 in circuit with either the load division relay 132 or the manual control switch 142 governing increase or decrease of the rate of firing manually. This manual control switch 142 comprises a pair of selectable contacts 143 and 144 and a selector contact 145, by which suitable battery potential from the battery bus 100 may be impressed upon either of the local control wires 149 and 150.

The local firing control wires 149 and 150 are connected directly to the windings of the increase and decrease control relays 153 and 154 for the coal feeder rheostat adjusting motor 73. Thereby, whenever potential is put upon either of the local firing control wires 149—150 the rate of coal feed is changed. The relay 153 closes a set of contacts 155 extending from the constant potential leads 75 to the armature 76 of the coal feed rheostat adjusting motor 73. The switch 155, controlled by the relay 154 applies potential from the bus 75 through the armature 76 of the coal feed rheostat adjusting motor 73 in reverse direction for shifting the rheostat 69 to a position which will decrease the rate of coal feed. The series rheostat 77, which is adjustable, is inserted in the circuit of the armature 76 so as to control the rate at which said motor 73 operates as compared with other motors in the group controlling combustion of the particular boiler.

The operation of the rheostat adjusting motor 56 for adjusting the speed of the induced draft fan 30 is normally under the control of the local firing control wires 149 and 150 and these are normally connected to the master controller, but any deviation from efficiency, as indicated by the efficiency meter 31, or any deviation from proper furnace pressure, as indicated by furnace pressure gauge 33, is arranged to interrupt the control of the induced draft fan 30 and of the forced draft fan 22, respectively, by the master controller or the hand controlled switch 142 or by the motor differential relay 135 and governed exclusively by the efficiency meter 31 and the furnace pressure gauge 33, respectively. This is accomplished as follows. The armature circuit of the induced draft rheostat controlling motor 56 is governed for increase by the increase controlling relay 157 and for decrease by the decrease controlling relay 158 which have corresponding forward and reverse connection con-

tactors 159 and 160 controlled thereby. The windings of these relays 157 and 158 have branch connections 163 and 164 cut through the normally closed relay contacts of the cut-in relays 169 and 170, which relays are under the control of the selector contact 162 of the efficiency meter 31. Thus the branch 163 for the increase relay 157 is cut through the contacts 165 of cut-in relay 170 and contacts 166 of cut-in relay 169. In a similar manner the branch 164 of the decrease relay 158 is cut through the contacts 167 of the cut-in relay 170 and of the contacts 168 of the cut-in relay 169. Hence, when either relay 169 or 170 is energized the branches 163 and 164 which lead to the local firing control wires 149 and 150 are disconnected.

The cut-in relay 169 has normally open contacts 174 for closing the branch connection 176 of the decrease relay winding 158 to battery and likewise the cut-in relay 170 has contacts 173 for closing the branch connection 175 from the winding of the increase relay 157 to battery to cause the same to operate respectively.

The efficiency meter selector contact 162 is arranged to close a circuit from positive battery wire 177 to either contact 179 leading to the increase cut-in relay 170 or contact 180 leading to decrease cut-in relay 169, and thereby energizing increase relay 157 through closing of contacts 173, or energization of decrease relay 158 through closing of contacts 174.

A manually operable transfer switch 178 takes control away from the automatic action of the efficiency meter and transfers the same to the hand switch 182. Then, by either pulling out the button 183 or pushing the same in, the increase relay 157 or the decrease relay 158, respectively, may be energized.

The forced draft fan rheostat control mechanism has the same relation with respect to the local firing control wires 149 and 150 and the furnace pressure gauge 33, which exists between the local firing control wires and the efficiency meter 31 for the induced draft fan controlling rheostat mechanism. That is to say, normally the branch circuits 187 and 188 for the increase and decrease relays 185 and 186, respectively, are connected through the contacts of the cut-in relays 189 and 190 to the local firing control wires 149 and 150. However, the furnace pressure gauge 33, through its selecting contact 184 and cooperating with the contacts 193 and 194, is able to energize the cut-in relay windings of the relays 189 and 190 and interrupt the branches normally connected to the local firing control wires and close the contact 195 or 196, as the case may be, to energize the increase and decrease relays 185 or 186.

A selector switch 192 is operable by hand to cut out the automatic control of the furnace pressure gauge 33 and transfer control to the manual switch 197, this switch having a selector contact and a button 198 so arranged that by pulling out on the button 198 the cut-in relay 190 may be energized to cause energization of the increase relay 185. When the button 198 is depressed the decrease relay 186 is energized accordingly.

Now, from the above it can be seen thus far that the speeds of the driving motors of the coal feeders, the induced draft fans and the forced draft fans are under the control of the corresponding rheostats 69, 53 and 58. An adjustment of the position of the rheostats changes the rate of firing. The master pressure gauge, act-

relay 135. Thus the control wire 129 is cut through the normally closed contacts 215 and 216 leading to the one set of contacts of the selector switch 138 and likewise the control wire 130 is cut 5 through the contacts 217 and 218.

Normally open contacts 219 and 220, under the control of the cut-in relays 213 and 214 are arranged to apply battery potential to the local firing control wires 149 and 150, respectively, under 10 the control of the voltage differential relay 135. The load division relay 133 for boiler No. 2 operates in the same manner for the controls of the second boiler under the control of its voltage differential relay 136.

15 The load balance bus has branches leading to the windings 202 of the relay 135, 222 of the relay 136 and 223 of the relay 137. The opposite windings 200, 224 and 225 may be connected to the load balance bus 204 through the plug switch 207, 20 in order to permit the potential of individual coal feeder potential bus to supply the potential to the load balance bus, as the master boiler, for determining the relation between the rates of firing of the various boilers. Thus, for example, boiler 25 No. 2 may be selected as the master boiler and the potential of its coal firing potential bus may be taken as the reference potential on the balancing coils of the respective voltage differential relays. Then, if through any difference in rate of 30 response of, for example, the rheostat adjusting motor, the potential and hence the rate of feeding of one of the coal feeders tends to vary from the predetermined ratio with respect to the master boiler, the voltage differential relay becomes unbalanced and through its load division relay cuts 35 into the local firing control wires of the particular boiler and adjusts the rate of firing accordingly. As soon as this regulating adjustment has been made the voltage differential relay comes to balance 40 and the operation proceeds in the proper relation.

If, due to variations in the total load, a lower rate of firing of the boiler is required, then the master controller, through the action of the master pressure gauge 2, or other load responsive 45 device, imposes upon the master control wires 129 and 130 for all of the boilers, impulses for energizing the decrease relays, for example, for operating the rheostat adjustment motors to decrease the voltage of the motor generator set 65, 50 the speed of the induced draft fan 30 and the speed of the forced draft fan 22 for each of the boilers.

If, in so doing, any unbalance as between fuel 55 and air is occasioned for any particular boiler, this is automatically adjusted by the efficiency meter of the particular boiler which seizes the control of the local firing control wires to make the necessary adjustment. Likewise, if any unbalance 60 between induced draft and forced draft in any particular boiler occurs, the furnace pressure gauge of that boiler assumes control of the local firing control wires of that boiler and makes a corrective adjustment. These corrective adjustments are made to the exclusion of the master controller. In the same manner, if any unbalance 65 in the rate of firing between boilers occurs, the voltage differential relays detect the difference and through the load division relays cut 70 into the control for the local firing control wires to the exclusion of the master control and make a regulating adjustment of fuel and air for that particular boiler.

The number of boilers which may thus be controlled is, within limits, anything desired.

The use of adjustable speed motors for driving the fans and fuel feeders as herein described is not an essential part of this invention. Instead of operating rheostats to regulate the elements of combustion, the regulating pilot motors could, 5 within the scope of this invention, operate dampers, vanes, or other draft or fuel regulating means. It is desirable, however, to employ adjustable speed motors for this purpose as the frictional resistance offered by the speed regulating rheostats is negligible and hence the relative speeds 10 of the pilot motors can be more closely adjusted.

The choice of which control element, the master controller or the corrective device, should have precedence over the other, is not an essential part 15 of this invention. Although this description is based on allowing the corrective controller to operate to the exclusion of the master controller, it could easily be arranged to give the precedence 20 to the master controller.

It is not necessary for an embodiment of my invention to have both induced and forced draft fans, as I intend to cover broadly fuel and air.

Hand controls may be substituted for automatic controls by selector switches and hand operated switches, as indicated on the drawings, at each point where an automatic device responsive to some action of the boiler or furnace is provided.

I do not intend to be limited to the details as 30 shown and described, except as the same are specifically recited in the appended claims.

I claim:

1. In a system of the class described, a furnace, a fuel feeding device for said furnace, a controller therefor, air supply means for said furnace, a controller therefor, means responsive to the demand upon the furnace for governing both controllers simultaneously and means responsive to the efficiency of combustion for exercising a governing action upon said second controller, and means for continuously excluding the governing action of said demand responsive means during the governing action of the efficiency responsive means. 45

2. In a system of the class described, the combination of a furnace, a fuel feeding device for said furnace, a controller therefor, air supply means for said furnace, comprising a forced draft producing means and an induced draft producing means, individual control means for both draft producing means, means responsive to the demand upon the furnace for governing all of said control means simultaneously and means responsive to efficiency of combustion for governing one of said draft controllers to the continuous exclusion of the governing action of said demand responsive means. 55

3. In combination, a furnace, a fuel feeding device for said furnace, a controller therefor, air supply means for the furnace comprising a forced draft producing means and an induced draft producing means, individual controllers for both draft producing means, means responsive to the demand upon the furnace for governing all of said controllers simultaneously and means responsive to furnace pressure for governing one of said draft controllers to the continuous exclusion of the governing action of said demand responsive means. 65

4. In a system of the class described, a furnace, a fuel feeding device for said furnace, a controller therefor, air supply means for said furnace comprising a forced draft producing means and induced draft producing means, indi- 70 75

- vidual controllers for both draft producing means, means responsive to the demand upon the furnace for governing all of said controllers simultaneously, means responsive to the efficiency of combustion for governing one of said draft controllers and means responsive to fire box pressure for governing the other of said draft controllers, in each case to the exclusion of the governing action of said demand responsive means.
10. 5. In a system of the class described, a plurality of furnaces, a plurality of individually operable fuel feeders for said furnaces, feed control means for each of said fuel feeders, adjustment varying means for said feed control means, means for controlling the adjustment varying means of all of the furnaces responsive to the demand upon said furnaces, means responsive to the rates of operation of said fuel feeders, and a differential element governed by the relative 10 rates of operation of said fuel feeders for controlling one of said adjustment varying means.
6. In a system of the class described, a plurality of furnaces, a plurality of individually operable fuel feeders for said furnaces, variable speed driving means for each of said fuel feeders, speed control means for each of said variable speed driving means, adjustment varying means for said speed control means, means for controlling the adjustment varying means of all of the 20 furnaces responsive to the load demands upon said furnaces, means responsive to the rates of operation of said fuel feeders, and a differential element governed by said last named means for controlling one of said adjustment varying means.
7. In a system of the class described, the combination of a furnace having fuel feed means, air supply means, means responsive at all times to the efficiency of combustion, a device responsive to the heat demand to be supplied by said furnace, regulating means periodically under the control of said device for regulating the action of both the fuel feed means and the air supply means in common, and adjusting means, governed by said efficiency responsive means, for adjusting the action of said air supply means and said fuel feed means relative to each other, said adjusting means being capable of acting at any time to the exclusion of said regulating means.
8. In combination, a furnace, a boiler, a steam load responsive means, a fuel feeding device, a variable speed drive therefor, means for supplying current flow of variable potential to said drive to vary the speed thereof, an adjustable rheostat for said current supply means, a timing controller, means governed by said load responsive means and acting through said timing controller for adjusting said rheostat, air supply means for said furnace, a variable speed drive therefor, a rheostat for governing said latter drive and means for automatically controlling the second rheostat individually to the exclusion of the control of said load responsive means.
9. In combination, a boiler, a pressure gauge therefor, a furnace for the boiler, a fuel feeder for the furnace, a rheostat for controlling the speed of the fuel feeder, a motor for adjusting said rheostat, air supply means, a rheostat for controlling the speed of the air supply means, a motor for adjusting said second rheostat, a pair of firing control wires for governing the operation of said motors under the control of said gauge, an efficiency meter for the furnace, and a relay for placing the second motor under the sole control of said efficiency meter so long as said meter indicates abnormal efficiency.
10. In combination, a boiler, a steam pressure gauge therefor, a furnace for the boiler, a fuel feeder for the furnace, a rheostat for controlling the speed of the fuel feeder, a motor for adjusting said rheostat, air supply means, a rheostat for controlling the speed of said air supply means, a motor for adjusting said second rheostat, a pair of firing control wires for governing the operation of said motors under the control of said gauge, a furnace pressure gauge and a relay for placing the second motor under the sole control of said furnace pressure gauge so long as said gauge indicates an abnormal furnace pressure.
11. The method of regulating the output of a boiler which comprises firing the boiler at a selected rate, periodically making adjustments of the firing rate at a definite rate of adjustment and varying the length of the periods in proportion to the deviation of the boiler output from a predetermined value.
12. The method of regulating the output of a battery of boilers which comprises, firing each of the boilers at a selected rate, periodically increasing or decreasing the firing rate of all of the boilers in proportion to the load demand upon the boilers, and adjusting the ratio of fuel to air of each boiler independently of said periodic adjustment.
13. The method of regulating the output of a battery of boilers which comprises firing each of the boilers at a selected rate, periodically increasing or decreasing the firing rate of all of the boilers in proportion to the load demand upon the boilers and adjusting the rate of firing one boiler with respect to the rate of firing another boiler independently of said periodic common regulation of the firing rate of all of the boilers.
14. The method of regulating the output of a battery of boilers which comprises firing each of the boilers at a selected rate, periodically increasing or decreasing the firing rate of all the boilers in proportion to the load demand upon the boilers, adjusting the ratio of fuel to air of each boiler independently of said periodic adjustment and adjusting the rate of firing one boiler with respect to the rate of firing another boiler, independently of said periodic common regulation of the firing rate of all the boilers.
15. In a boiler control system, the combination of a furnace having fuel supply means, a fan for supplying air to said furnace, a variable speed drive for the fan, said drive comprising a constant speed type A. C. motor for supplying power to the fan, a D. C. machine connected in differential relation to the fan and said A. C. motor for supplying a suitable increment or decrement of power to secure the desired speed of the fan, a rheostat for definitely controlling the speed of the D. C. machine, and automatic controlling means for adjusting said rheostat to govern the speed of the fan.
16. In a control system, a series of furnaces, fuel supply means for the furnaces, air supply means for the furnaces, rheostats for controlling said supply means, motors for operating said rheostats, means for closing the circuits of said motors in common, and a rheostat in series with the motors of one furnace for controlling the rate of responses of the said motors of one furnace with respect to the rate of response of the motors of another furnace.
17. In combination, a battery of boilers, a load

responsive device common to the battery, furnaces for said boilers, each furnace having a fuel feed device, a variable speed motor therefor, a source of variable potential for controlling the speed of said motor, an air supply device, a variable speed motor therefor, governing means for said second motor, a pair of adjusting means for said pair of governing means, means for controlling the relative rates of action of one of said 5 adjusting means with respect to the other adjusting means for each boiler, means for governing the relative rates of operation of one pair of adjusting means for one boiler with reference to the rate of operation of another pair of adjusting means for another boiler and a common timing controller for periodically placing the adjusting means of all the boilers in common under the control of said load responsive device, load apportioning means for comparing the potentials 10 of the said sources of variable potential of the respective boilers, the adjusting means of each boiler being under the control of said load apportioning means, and means for each furnace responsive to the efficiency of combustion, said 15 adjusting means for controlling the air supply device of each furnace being also subject to the control of the efficiency responsive means of the respective furnaces.

18. In combination, a battery of boilers, a load responsive device common to the battery, furnaces for said boilers each furnace having a fuel feed device, a variable speed motor therefor, a source of variable potential for controlling the speed of said motor, an air supply device, a variable speed motor therefor, governing means for said second motor, a pair of adjusting means for said pair of governing means, means for controlling the relative rates of action of one of said adjusting means with respect to the other adjusting means for each boiler, means for governing the relative rates of operation of one pair of adjusting means for one boiler with reference to the rate of operation of another pair of adjusting means for another boiler and a common timing controller for periodically placing the adjusting means of all the boilers in common under the control of said load apportioning means.

19. In combination, a battery of boilers, a load responsive device for said battery of boilers, furnaces for said boilers, each furnace having a fuel feed device, a variable speed motor therefor, a source of variable potential for controlling the speed of said variable speed motor, governing means for said source, an air supply device, a variable speed motor therefor, governing means for said last named motor, a pair of adjusting means for said pair of governing means and means for controlling the relative rates of action of said adjusting means for each boiler, a common timing controller for the battery of boilers for periodically placing the adjusting means of all the boilers in common under the control of said load responsive device, load apportioning means for comparing the potentials of the said sources of variable potential of the respective boilers, the 50 adjusting means of each boiler being under the control of said load apportioning means.

20. In combination, a battery of boilers, a load responsive device for said battery of boilers, furnaces for said boilers, each furnace having a fuel feed device, a variable speed motor therefor, a

source of variable potential for controlling the speed of said variable speed motor, governing means for said source, an air supply device, a variable speed motor therefor, governing means for said last named motor, a pair of adjusting means for said pair of governing means and means for controlling the relative rates of action of said adjusting means for each boiler, a common timing controller for the battery of boilers for periodically placing the adjusting means of all the boilers in common under the control of said load responsive device, and means for each furnace responsive to the efficiency of combustion, said adjusting means for controlling the air supply device of each furnace being subject to the control of the efficiency responsive means of the respective furnaces.

21. In combination, a battery of boilers, a load responsive device for said battery of boilers, furnaces for said boilers, each furnace having a fuel feed device, a variable speed motor therefor, a source of variable potential for controlling the speed of said variable speed motor, governing means for said source, an air supply device, a variable speed motor therefor, governing means for said last named motor, a pair of adjusting means for said pair of governing means and means for controlling the relative rates of action of said adjusting means for each boiler, a common timing controller for the battery of boilers for periodically placing the adjusting means of all the boilers in common under the control of said load responsive device, load apportioning means for comparing the potentials of the said sources of variable potential of the respective boilers, the adjusting means of each boiler being under the control of said load apportioning means, and means for each furnace responsive to the efficiency of combustion, said adjusting means for controlling the air supply device of each furnace being also subject to the control of said efficiency responsive means of the respective furnaces.

22. In combination, a battery of boilers, a load responsive device common to the battery, furnaces for said boilers each furnace having a fuel feed device, a variable speed motor therefor, a source of variable potential for controlling the speed of said motor, an air supply device, a variable speed motor therefor, governing means for said second motor, a pair of adjusting means for said pair of governing means, means for controlling the relative rates of action of one of said adjusting means with respect to the other adjusting means for each boiler, means for governing the relative rates of operation of one pair of adjusting means for one boiler with reference to the rate of operation of another pair of adjusting means for another boiler and a common timing controller for periodically placing the adjusting means of all the boilers in common under the control of said load responsive device.

23. In combination, a boiler, a steam pressure gauge for the boiler, a furnace for the boiler, a fuel feed for the furnace, a controller for the fuel feed, an adjusting motor for the controller, a pair of firing control wires selectively energized by said gauge, a timing controller for periodically subjecting the firing control wires to the control of said gauge and relays for closing the connections of said adjusting motors for forward or reverse operation, said relays being selectively controlled by said firing control wires.

24. In combination a boiler, a steam pressure gauge therefor, a furnace for the boiler, a fuel feed for the furnace, a controller for the fuel

feed and an adjusting motor for the controller, an air supply means, a controller for the air supply means, an adjusting motor for said second controller, rheostats for controlling the rates of response of said adjusting motors and means under the control of the gauge for energizing said adjusting motors simultaneously.

25. In combination, a boiler, a steam pressure gauge therefor, a furnace for the boiler, a fuel feed for the furnace, a controller for the fuel feed, and an adjusting motor for the controller, an air supply means, a controller for the air supply means, an adjusting motor for said second controller, rheostats for controlling the rates of response of said adjusting motors and means under the control of the gauge for energizing said adjusting motors simultaneously, an efficiency meter for the furnace and means under the control of the efficiency meter for individually controlling the second adjusting motor.

26. In combination, a boiler, a steam pressure gauge therefor, a furnace for the boiler, a fuel feed for the furnace, a controller for the fuel feed, an adjusting motor for the controller, an air supply means, a controller for the air supply means, an adjusting motor for said second controller, rheostats for controlling the rates of response of said adjusting motors, firing control wires, relays under the control of said firing control wires for closing the circuits of said adjusting motors simultaneously for forward or reverse motion, said firing control wires being under the control of said gauge.

27. In combination, a plurality of boilers, furnaces for said boilers, firing means for each furnace, variable speed motors for driving said firing means, rheostats for controlling the speed of said motors, power supply mains for the motors of each boiler, means for varying the potential of said mains to adjust the relative speeds of said motors, adjusting motors for said rheostats, means for varying the rate of operation of the adjusting motors relative to each other, relays for closing the circuits of said adjusting motors to said mains for forward or reverse operation, firing control wires for said relays and a master controller comprising a load responsive device for energizing the firing control wires selectively when the output of the boilers deviates from a predetermined value.

28. In combination, a plurality of boilers, furnaces for said boilers, firing means for each furnace, variable speed motors for driving said firing means, rheostats for controlling the speed of said motors, power supply mains for the motors of each boiler, means for varying the potential of said mains to adjust the relative speeds of said motors, adjusting motors for said rheostats, means for varying the rate of operation of the adjusting motors relative to each other, relays for closing the circuits of said adjusting motors to said mains for forward or reverse operation, firing control wires for said relays and a master controller comprising a load responsive device for energizing the firing control wires selectively when the output of the boilers deviates from a predetermined value, a differential relay for comparing the firing rate of one boiler with the firing rate of another boiler and means controlled by said differential relay, upon deviation of the firing rates from a predetermined ratio, for removing control of the firing control wires of one boiler from the master controller and assuming control of the same.

29. In combination, a plurality of furnaces, fir-

ing means for each furnace, a variable speed motor for each firing means, a source of variable potential for each motor to control the speed thereof, governing means for each source for varying the potential thereof, a differential relay controlled by said sources of variable potential, said governing means being controlled by said differential relay to vary the relative rates of firing of said furnaces.

30. In combination, a plurality of furnaces, firing means for each furnace, a variable speed motor for each firing means, a source of variable potential for each motor to control the speed thereof, governing means for each source for varying the potential thereof, a differential relay controlled by said sources of variable potential, said governing means being controlled by said differential relay to vary the relative rates of firing of said furnaces, and a total load responsive element for said furnaces, said governing means being under the control of said load responsive element for variations of total load.

31. In combination, a battery of boilers, a load responsive device for said battery of boilers, furnaces for said boilers, each furnace having a fuel feed device, a variable speed motor therefor, a source of variable potential for controlling the speed of said variable speed motor, governing means for said source, an air supply device, a variable speed motor therefor, governing means for said last named motor, a pair of adjusting means for said pair of governing means and means for controlling the relative rates of action of said adjusting means for each boiler, a common timing controller for the battery of boilers for periodically placing the adjusting means of all the boilers in common under the control of said device.

32. In a furnace control system, means for regulating the air supply, means including a normally inoperative pilot motor for adjusting the regulating means, means responsive to predetermined conditions for controlling the adjusting means, additional means controlling the adjusting means responsive to the demand on the furnace, and means for rendering one of said two controlling means ineffective during the entire period of regulation of the air supply means by the other controlling means.

33. In a furnace control system, means for regulating the air supply, means including a normally inoperative pilot motor for adjusting the regulating means, means responsive to predetermined conditions for controlling the adjusting means, additional means controlling the adjusting means responsive to the demand on the furnace, means for rendering one of said two controlling means ineffective during the entire period of regulation of the air supply means by the other controlling means, fuel feed means, and means for controlling the fuel feed means responsive to the demand on the furnace.

34. In combination, a furnace fuel feeding device, a furnace air feeding device, separate controllers for said devices, means including a normally inoperative pilot motor for adjusting each of said controllers, means responsive to the demand upon the furnace for governing both adjusting means simultaneously, means responsive to the efficiency of combustion for exercising governing action upon one of said adjusting means, and means effective at all times for preventing the simultaneous governing action of said one adjusting means by both of said responsive means.

35. In combination, a furnace fuel feeding de-

vice, a furnace air feeding device, separate controllers for said devices, means including a normally inoperative pilot motor for adjusting each of said controllers, means responsive to the demand upon the furnace for governing both adjusting means simultaneously, means responsive to the efficiency of combustion for exercising governing action upon one of said adjusting means, and means effective at all times for preventing the simultaneous governing action of said last named adjusting means by both of said responsive means, said last named adjusting means being always under the control of one of said responsive means regardless of the condition of the other responsive means.

36. In combination with a battery of furnaces supplying a common load and having variable air supply means and fuel supply means, means including a normally inoperative pilot motor for adjusting each of said means, controlling means common to all of the furnaces for controlling the air and fuel supply adjusting means at the respective furnaces responsive to variations in the load, additional controlling means individual to the respective furnaces for controlling the air supply adjusting means responsive to predetermined conditions, and means individual to each furnace and at all times under the control of one of said controlling means for excluding regulation of the air supply by the other controlling means during the entire period of action of said one controlling means.

37. In combination with a battery of furnaces, means for regulating the fuel supply to the respective furnaces, means associated with each furnace for comparing its rate of fuel supply with that of another furnace, and means controlled by said last named means for controlling the fuel regulating means of its associated furnace to maintain a predetermined ratio of fuel feed between its furnace and that of the other furnace.

38. In combination with a battery of furnaces carrying a common load, variable fuel supply means and air supply means for each furnace, means for automatically maintaining a predetermined fuel to air ratio in each furnace, means for varying the fuel and air supply to the respective furnaces responsive to variations in the common load, and means for comparing the loads carried by the respective furnaces and for automatically maintaining a predetermined load distribution between the furnaces.

39. In combination with a plurality of furnaces carrying a common load, variable fuel supply means and air supply means for each furnace, means for automatically maintaining a predetermined fuel to air ratio in each furnace, means for varying the fuel and air supply to the respective furnaces responsive to variations in load, and means for comparing the load carried by one of the furnaces with that carried by each of the other furnaces and for maintaining a predetermined ratio between the loads on each of said other furnaces and the load on said one furnace.

40. In combination with a plurality of furnaces carrying a common load, variable fuel supply means and air supply means for each furnace, means for automatically maintaining a predetermined fuel to air ratio in each furnace, means for varying the fuel and air supply to the respective furnaces responsive to variations in load, means for comparing the load carried by one of the furnaces with that carried by each of the other furnaces and for maintaining a predetermined ratio between the loads on each of said other

furnaces and the load on said one furnace, and means operable for selecting any one of the furnaces to constitute the standard with which the other furnaces are compared.

41. A combustion control system comprising in combination with a battery of furnaces having a common demand, each furnace having means for feeding thereto the elements of combustion, regulating means for said feeding means, each of said regulating means including a pilot motor normally inoperative, a common means responsive to the demand for effecting a simultaneous operation of said motors at substantially constant predetermined speeds, and means for adjustably fixing the relative rates at which the regulating means adjust the feeding means, said last named means including adjustable rheostats in the pilot motor circuits for establishing the relative predetermined pilot motor speeds. 5

42. A combustion control system comprising in combination with a battery of furnaces having a common demand, each furnace having a plurality of means for controlling the various conditions of combustion, regulating means for each of the controlling means comprising separate pilot motors normally inoperative, a common means responsive to the demand for effecting a simultaneous operation of said motors at substantially constant predetermined speeds, and means for adjustably fixing the relative rates at which the pilot motors of each furnace adjust the controlling means, said last named means including a rheostat in common with all of the pilot motor circuits of each furnace for adjustably establishing the relative predetermined pilot motor speeds. 20 25 30 35

43. A combustion control system comprising in combination with a furnace having a plurality of means for controlling the various conditions of combustion, regulating means for each of the controlling means comprising separate pilot motors normally inoperative, means for effecting an operation of said motors at a substantially constant predetermined speed, and means for adjustably fixing the rate at which the pilot motors adjust the controlling means, said last named 40 means including a rheostat in common with all of the pilot motor circuits for adjustably establishing the predetermined pilot motor speeds and at least one rheostat individual to a pilot motor circuit for adjusting the relative predetermined 45 50 speeds of the pilot motors.

44. A combustion control system comprising in combination with a furnace having a plurality of means for feeding thereto various elements of combustion, regulating means for each of the feeding means comprising separate pilot motors normally inoperative, means for effecting a simultaneous operation of said motors at a substantially constant predetermined speed, and means for adjustably fixing the relative rates at which the 55 various regulating means adjust their feeding means, said last means including adjustable rheostats in the various pilot motor circuits. 60

45. In combination with a furnace, variable means for feeding thereto one of the elements of combustion, said means including a feeding motor and an adjusting motor, variable means for feeding another element of combustion and including a second feeding motor and a second adjusting motor, a common supply bus for said adjusting 70 motors, separate variable rheostats in the respective adjusting motor circuits for controlling the relative rates of response of the adjusting motors, means effective responsive to predetermined 75 conditions for simultaneously connecting and dis-

connecting the adjusting motors to the bus, and a variable rheostat in the bus circuit for simultaneously controlling the rates of response of the adjusting motors.

5 46. In combination with a furnace, variable means for feeding thereto one of the elements of combustion, said means including a feeding motor and an adjusting motor, variable means for feeding another element of combustion and including another feeding motor and another adjusting motor, separate variable rheostats in the respective adjusting motor circuits for controlling the relative rates of response of the adjusting motors, and means for simultaneously energizing and deenergizing both of said adjusting motors.

10 47. In a control system, a furnace, fuel supply means and air supply means for the furnace, devices for controlling said supply means, pilot motors for controlling said devices, means for simultaneously closing and opening the circuits of said motors in common, and an adjustable rheostat in the pilot motor circuits for adjusting the rate of response of said motors.

15 48. In a combustion control system, an electric motor for varying one of the elements of combustion, a controller therefore, adjusting means for said controller including a normally inoperative pilot motor, separate control circuits for the pilot motor each controlled responsive to different predetermined conditions, and means responsive to the control of the pilot motor over one circuit for producing a gap in the other circuit.

20 49. In a combustion control system, motor driven means for supplying one of the elements of combustion, means for varying the speed of the motor driven means said speed varying means being actuated by a normally inoperative pilot motor, means controlled in accordance with variations in predetermined conditions for governing the speed varying means, means controlled in accordance with variations in other predetermined conditions for governing the speed varying means, and means for preventing the simultaneous control of the speed varying means by both of the governing means.

25 50. In combination, a plurality of variable speed motors, separate rheostats for varying the speeds of the respective motors, separate normally inoperative pilot motors for controlling the respective rheostats, means for simultaneously energizing and de-energizing said pilot motors and variable resistors individual to certain of the pilot motors for adjustably fixing the relative extents of motion of the rheostats during the period of energization.

30 51. In combination, a plurality of variable speed motors, separate resistors for varying the speeds of the respective motors, separate normally inoperative pilot motors for controlling the respective resistors, means for effecting an operation of said pilot motors at substantially constant predetermined speeds, variable rheostats individual to certain of the pilot motors for adjustably fixing the relative predetermined constant speeds of the pilot motors, and a variable rheostat in common to the pilot motors for adjusting the predetermined speeds of all of the pilot motors in unison.

35 52. A control system for apparatus having a plurality of factors which tend to vary from predetermined values during operation of said apparatus, means for maintaining said factors at said predetermined values comprising means for

causing an adjustment of the values of the factors, constant speed normally inoperative pilot motors which when operated tend to operate said last named means; a common resistor for adjusting the predetermined speeds of the pilot motors in common, and individual resistors for the respective pilot motors for adjustably fixing the relative predetermined speeds of the pilot motors.

40 53. In combination with a furnace having means for feeding thereto the elements of combustion, a combustion control system comprising regulating means for each of said feeding means, means responsive to the demand including a timing controller for periodically effecting a simultaneous adjustment of said regulating means, means for adjustably setting the rate at which said last named means regulate said feeding means to maintain approximately correct proportions of feed during said adjustment, and means responsive to predetermined conditions for effecting individual adjustments of said regulating means to correct the relative rates of feed.

45 54. In a control system for a furnace, fuel supply means and air supply means for the furnace, devices for controlling said supply means, pilot motors for adjusting said devices, means for simultaneously closing and simultaneously opening the circuits of said motors in common, and adjustable rheostats in certain of the pilot motor circuits for adjusting the relative extents of adjustment of said control devices.

50 55. In a control system for a furnace, fuel supply means and air supply means for the furnace, devices for controlling said supply means, pilot motors for adjusting said devices, means including a timing controller for energizing and de-energizing said pilot motors, whereby each of the motors receives energy for a predetermined interval of time, and adjustable rheostats in certain of the pilot motor circuits for adjusting the relative extents of adjustment of said control devices during the interval of energization.

55 56. In combination with a furnace having means for feeding thereto the elements of combustion, a combustion control system comprising a regulating means for each of said feeding means, a normally inoperative pilot motor for adjusting each of said regulating means, demand responsive means including a timing controller for energizing all of said pilot motors during a timed interval, and resistors individual to certain of the pilot motors for predetermined the numbers of revolutions of the respective pilot motors during said interval of energization.

60 57. In combination, a furnace, a fuel feed for the furnace, a controller for the fuel feed, an adjusting motor for the controller, an air supply means, a controller for the air supply means, an adjusting motor for said second controller, means responsive to the heat demand on said furnace for operating said adjusting motors over equal intervals of time, and an adjustable resistor individual to at least one of said adjusting motors for setting the relative amounts of adjustment of said controllers during each of said equal time intervals.

65 58. In a control system, a pair of control devices, adjusting motors for said devices, means responsive to predetermined conditions for intermittently energizing said motors, both motors receiving equal periods of energization, and means for co-ordinating the amounts of adjustment of said devices during the periods of energization,

said co-ordinating means including an adjustable resistor in the circuit of at least one of the motors.

59. In combination with a furnace having supply means for feeding thereto the elements of combustion, regulators for said supply means, adjusting motors for said regulators, means responsive to the heat demand on the furnace for transmitting intermittent control impulses, the length of each impulse being timed in accordance with predetermined conditions, means for effecting energization of said motors during an interval of a length determined by the length of the impulse, and a resistor individual to the circuit of each of said motors for adjustably setting the

extents of adjustment of the respective controllers during said interval of energization.

60. In a system of combustion control for furnaces, the combination of supply means for feeding the elements of combustion, regulating means for said supply means, adjusting means for said regulating means, control means for effecting adjustments of each of said regulating means during a timed interval, and means individual to certain of said adjusting means for adjustably setting the relative amounts of adjustment during said timed interval. 5 10
